UNITED STATES PATENT OFFICE.

HERBERT WEINBAUM AND LOUIS M. FERBER, OF BRONX, AND HENRY LEONARD, OF BROOKLYN, NEW YORK.

DISPENSING CONTAINER.

Application filed August 7, 1922, Serial No. 580,224.

To all whom it may concern:

Be it known that we, HERBERT WEINBAUM, LOUIS M. FERBER, and HENRY LEONARD, citizens of the United States of America, 5 residing at Bronx and Brooklyn, respectively, in the counties of Bronx and Kings, respectively, and State of New York, have invented new and useful Improvements in Dispensing Containers, of which the following is a specification.

This invention relates to dispensing containers or cans.

Some of the objects of the present invention are: to produce a can of the character 15 mentioned with which condiments or granular commodities may be discharged therefrom in predetermined charges or quantities; to produce a dispensing can having a plurality of spring actuated closure members 20 one of which is pivotally mounted and the other of which is slidably mounted and both of which are operable simultaneously and which are opened and closed respectively at the same time; to arrange the said closure 25 members at the outlet of the can which is embodied by a detachable cover for the can proper; and with these and other objects in view the invention resides in the particular provision, relative disposition and operation of parts hereinafter fully described and 30 illustrated in the accompanying drawing, in which:—

Figure 1 is a side elevation of the dispensing can of the present invention.

Figure 2 is a central vertical sectional view through the outlet of the can showing the closure members both in closed position and in open positions.

Figure 3 is a sectional view taken on the 40 line 3—3 of Figure 2.

Figure 4 is a perspective view of the slide closure guide member.

Referring now more particularly to the several views of the drawing, it will be apparent that, the can of the present invention will essentially include a can proper or container 10 and a cover 11 which is removably attached to the can proper. The cover 11 embodies an outlet 12 through which the 45 contents of the can proper passes. In the present instances the outlet 12 is formed by the cylindrical reduced portions of the cover 11. A cylindrical member 13 fits within the outlet 12 and the said member 13 is 50 hollow, having beveled portions interiorly

thereof and dove-tail as at 14. The member 13 is open at the opposite ends thereof, and the upper end is opened and closed by a closure member 15 in the nature of a slide which moves through the wall of the outlet 60 12 and in the dove-tail of the member 13. The member 15 has portions 16 which support a member 17 embodying a shoulder 18. A spring 19 surrounds the member 17 and disposed between the wall of the outlet and 65 one of the portions 16 to render the closure member 15 automatically operable to maintain the same in a normal open position. Arranged beyond the closure member 15 in the outlet 12 is a second closure member 70 20 which is pivotally mounted as at 21 to a companion member 22 formed on a cylindrical fitting 23 which fits in the outlet 12. In order to effect the movement of the closure member on its pivot, there is provided 75 an extension or tail 24 on the member 20, which tail, has a slot 25 or the like in the extreme end thereof which accommodates the reduced portion of the member 17. The shoulder 18 of the member 17 engages one 80 side of the tail 24, whereas, one portion 16 of the closure member 15 engages the opposite side of said tail. It follows, that upon movement of the closure member 15 to a closed position, the shoulder 18 in engagement with the tail 24 will move the closure member 20 on its pivot to an open position as shown in dotted lines in Figure 2, and upon release the closure member 15 by virtue 85 of the spring 19 will move to an open position and the portion 16 in engagement with the tail 24 will move the closure member 20 to a closed position as shown in full lines in Figure 2. It will now be manifest that the closure members 15 and 20 are operable 90 simultaneously and that they are in open and closed positions at the same time. The closure member 20 is concaved and is in the nature of a spoon to facilitate the discharge of the charge of sugar or whatever 95 other condiment or commodity is in the can. The lower end of the fitting 23 is cut out to accommodate the member 17 to allow the same to have movement. A push button 26 is employed to facilitate the movement 100 of the closure member 15.

From the foregoing, it will be manifest that, the features of the present invention may be embodied by a container, receptacle or bowl as a dispensing device for restau- 110

rants and similar places; and by eliminating certain features other forms of dispensing containers or cans may be produced.

In using the device shown in the drawing, the same is first inverted which allows a certain amount of the substance to pass to the members 20 and 22. Upon manipulation of the member 15, the same may be pressed inwardly to cut off the passage of 5 the substance in the container 10, and allows the charge held by the members 20 and 22 to be discharged inasmuch as the member 20 will be moved on its pivot to an open position while the member 12 is in a closed 10 position.

It is to be understood that the right is here reserved to make changes, alterations, and modifications within the scope of the claims hereunto appended whenever it is 15 deemed desirable or necessary.

What is claimed is:

1. A dispensing container having an outlet at which are arranged a pivotally mounted spoon shaped closure member and 20 a horizontal slidable closure member, and means which holds the spoon shaped closure member normally in a closed position and the slidable closure member normally 25

in an opened position, the said means being operable to move closure members simultaneously to reverse the positions thereof, said first mentioned closure member including a stationary part and a movable part having a tail for co-action with said horizontal closure member. 30

2. In a device of the class described, the combination with a container having a neck, a spoon shaped closure member insertible in the neck, said spoon shaped closure member comprising a stationary part having a tail 35 and a co-acting pivoted part, a horizontal closure member mounted in the neck of the container, manipulative means for co-action with said tail for simultaneously moving said pivoted part with relation to said stationary part to open said spoon shaped closure member and to move said horizontal closure member to a closed position, and automatic means for returning both of said closure members to normal position. 40

In testimony whereof we have affixed our signatures.

HERBERT WEINBAUM.
LOUIS M. FERBER.
HENRY LEONARD.
